(57) **CLAIM**

The ornamental design for an ergonomic tweezer, as shown and described.

DESCRIPTION

A portion of the disclosure of this patent document contains material which is subject to copyright protection. This patent document may show and/or describe matter which is or may become trade dress of the owner. The copyright and trade dress owner has no objection to the facsimile reproduction by anyone of the patent disclosure as it appears in the Patent and Trademark Office patent files or records, but otherwise reserves all copyright and trade dress rights whatsoever.

FIG. 1 is a top left-side perspective view of an ergonomic tweezer;

FIG. 2 is a top right-side perspective view thereof;

FIG. 3 is a front view thereof;

FIG. 4 is a back view thereof

FIG. 5 is a right-side view thereof;

FIG. 6 is a left-side view thereof;

FIG. 7 is a top view thereof; and,

FIG. 8 is a bottom view thereof.

The broken lines in the figures are for the purpose of illustrating portions of the ergonomic tweezer, which form no part of the claimed design.
